(57) **CLAIM**

The ornamental design for a holder for drying a paintbrush, as shown and described.

DESCRIPTION

FIG. 1 is a perspective view of a holder for drying a paintbrush showing my new design with the broken lines showing a paintbrush veing for illustrative purposes only and forming no part of the claimed design;

FIG. 2 is an enlarged elevational view of the inside of the holder shown in its unfolded condition;

FIG. 3 is a side elevational view taken in the direction of arrow 3 in FIG. 2, the opposite side being a mirror image; FIG. 4 is an elevational view of the outside of the holder taken in the direction of arrow 4 in FIG. 3;

FIG. 5 is a top plan view taken in the direction of arrow 5 in FIG. 2; and,

FIG. 6 is a bottom plan view taken from the direction of arrow 6 FIG. 2.
